STENCIL OPERATING MACHINE

Filed Sept. 15, 1924

2 Sheets-Sheet 2

FIG. 3.

FIG. 4.

Inventor

Charles Eckman

By his Attorney, Israel Benjamins.

UNITED STATES PATENT OFFICE.

CHARLES ECKMAN, OF ROSELLE PARK, NEW JERSEY.

STENCIL-OPERATING MACHINE.

Application filed September 15, 1924. Serial No. 737,783.

To all whom it may concern:

Be it known that I, CHARLES ECKMAN, a citizen of the United States, residing at 310 East Clay Ave., Roselle Park, in the 5 county of Union and State of New Jersey, have invented a new and useful Stencil-Operating Machine, of which the following is a specification.

My invention relates to improvements in 10 stencil operating machines, such as used in the manufacture of signs, posters, felt pennants, for putting designs on cloth, wood and glass, for stencilling metal plates and for similar work, wherein sheets of paper, 15 cardboard or other material are fed on to a table by hand and a stencil frame or holder, having a suitable stencil or screen secured thereto at the underside thereof is brought down upon the said sheets of paper, card 20 board or other material to print thereon a suitable design or picture.

One of the objects of my invention is to impart a vertical motion to the stencil frame or holder and to keep the same in a horizontal position when raised, thereby affording ample room for feeding the paper on to 25 the table.

Another object of my invention is to enable the operation of the stencil frame to be 30 performed by foot power or motor power; instead of by hand power, as is done at present, although my improved machine may also be designed to be operated by hand, if desired.

Another object of my invention is to 35 design an improved stencil operating machine, which is simple, durable and inexpensive.

Other objects and advantages will herein- 40 after appear, and parts of my improvement may be used without other parts.

I attain these objects by the stencil operating machine, one form of which is illustrated in the accompanying drawings or by 45 any mechanical equivalent or obvious modifi- cation of the same.

In the drawings Fig. 1 is a plan or top view of my stencil operating machine;

Fig. 2 is a front elevation of the same; 50 and Fig. 3 is an end elevation looking from left to right in Fig. 1.

Fig. 4 is a detail of a clamp for holding down and for adjusting the position of the rear longitudinal bar of the stencil frame;

and Fig. 5 is a detail of the connection of 55 the front longitudinal bar of the stencil frame to the top horizontal bar joining the two vertical supports of the stencil frame, which are hereinafter more fully described.

Similar numerals refer to similar parts 60 throughout the several views.

11 designates the legs of a table or stationary part of my stencil operating machine for feeding thereon sheets of paper, cardboard and other material, and 12 the top of the said table; the said legs 11 are 65 joined by a pair of longitudinal braces 13 and by pairs of upper and lower cross braces 14 and 15 respectively.

Each of said cross braces is shown as having secured thereto a pair of metal sockets 70 16 by means of their flanges 17, which may be fastened to said cross braces by wood screws, bolts or in any other suitable manner.

The pairs of upper and lower sockets 75 16 serve as guides for the vertical rods or plungers 18, to slide therein; said rods 18 are shown as having at their ends horizontal arms 19, which terminate in flanges 20, which may be secured to said arms 19 in 80 any suitable manner; the arms 19 may be made separate from the said rods 18 and secured thereto by suitable elbows or fittings, if desired.

The rods 18 and arms 19 may also be made 85 tubular, if desired.

The flanges 20 may be secured to a pair 90 of supports or movable frames 21-22, which are situated on both sides of my stencil operating machine; each support is shown in Fig. 3 as consisting of a side bar 21, which is mounted edgewise thereof on a vertical frame 22, which is shown as consisting of three vertical bars joined at the top thereof by the said side bar 21 and at the bottom 95 thereof by short cross-bars.

The supports may be of any other suitable construction, if desired.

The two side bars 21 are joined above the 100 top of the table 12 by the front top bar 23 and the rear top bar 24, the latter of which is secured at its ends and the former of which is detachably connected to each of said side bars 21.

The stencil frame is shown as consisting 105 of the front longitudinal bar 25, the rear

longitudinal bar 26 and the cross bars 27 and 28, which are secured at their ends to said longitudinal bars 25 and 26, transversely thereto.

5 The front longitudinal bar 25 of the stencil frame may be adjustably connected to said front top bar 23 by means of a pair of detachable hinges 29, each having therein a removable pin 30 and a cap 31 which may 10 be removably connected to the tail end of the pin 30, to keep the same in position, as is shown in Fig. 5.

The rear longitudinal bar 26 of the stencil frame is adjustably secured at its ends to 15 the side bars 21 by means of a pair of vertical screws 49, nuts 50 and clamps 51 which are shown in Fig. 4, one at each end of the bar 26; by means of a pair of horizontal screws 52 and heads 53 the bar 26 may be 20 adjusted horizontally, from front to rear, on said side bars 21 before being clamped down as above described.

By means of the above arrangement frames of different sizes may be interchangeably 25 mounted on said side bars 21; where the sizes of said frames from front to rear differ considerably, the adjustment may be effected by moving the bars 23 and 25 until the bar 26 is near the desired position thereof, when 30 the bar 23 may be connected by a pair of bolts passing therethrough at the ends thereof and through a pair of openings 48 in the side bars 21; the screw 49 is then passed through one of the series of vertical openings 48, provided in the side bars 21, which is nearest to the bar 26 in front thereof, as 35 shown in Figs. 1 and 4, and the final adjustment of the bar 26 is then made by the horizontal screws 52 as above described.

40 To operate the supports 21—22, I provide at the lower ends thereof extensions 32, which are pivotally connected to a pair of operating levers 33 by means of pins 36; the said levers 33 are shown in Fig. 3 as pivotally connected to a pair of rocking links 34 by means of pins 37, and the links 34 are pivotally connected to the lower cross braces 15 of the table of my machine by means of pins 38.

50 At their front ends the levers 33 are shown as having secured thereto the ends of a foot board 35.

To raise the supports 21—22 with the stencil frame mounted thereon, the operator 55 has to depress the foot board 35, which causes the levers 33 to lift the extension 32 of the side frames 22 of said supports 21—22; the rods 18, sliding in their sockets 16, keep the motion of the supports vertical and the 60 stencil frame parallel to the table throughout all of its positions; the rocking links 34 take up the irregularity of the motion of the levers 33, as may easily be seen from Fig. 3.

65 To lower the supports 21—22 with the

stencil frame thereon more promptly than may be done by the weight thereof, suitable springs may be provided for the purpose; or they may be lowered mechanically in any suitable manner.

70 My stencil operating machine may also be driven by a motor or power from any other source; it may also be operated by hand, if desired, instead of by foot.

To direct the position of the sheets of 75 paper or cardboard, which are fed on to the table under the stencil frame, I provide the movable fingers or registers 42 and 43, respectively at the side and rear of the position of the sheets of material, under the 80 stencil frame, which registers are to move with the said supports and stencil frame.

To carry the said registers, I provide the rear beam 39 and the front beam 40, which 85 may be secured to the frames 22 at the rear and front thereof, as shown in Fig. 3, also the cross-beam 41, which is mounted on the said beams 39 and 40, transversely thereto.

The rear beam 39 has adjustably secured 90 thereto the fingers or registers 43; and the cross beam 41, the fingers or registers 42, by means of the feed-screws 46, each of which is formed at the upper end of a vertical bolt or pin, which passes through a 95 metal bearing 47, which is provided with flanges, to be secured to the underside of said beams 39 and 40; said bolts or pins are provided with collars 44 and 45, which may be secured thereto in any suitable manner; the collars 44 and 45 are resting on the beams 41 and 39 respectively, and the screws 46 at the ends of said pins are in engagement with nuts 54, which may be secured to or made in one piece with said registers 42 100 and 43; the upper ends of said registers pass through slots formed in metal sockets 55, which may be secured to the underside of 105 the table.

The fingers or registers 42 and 43 are 110 shown in Fig. 1 as rectangular in cross section, to prevent rotation thereof in their sockets 55; but they may have any other suitable shape, if desired.

By turning said screws 46 in their bearings 47 the nuts 54 with the registers 42 and 43 may be moved upwardly or downwardly, thereby adjusting the position of the upper ends of said registers with relation to the stencil frame, to allow for different thicknesses of stencil frames that may be employed and to insure perfect register of the work.

Many changes may be made in the details 120 of my stencil operating machine without departing from the main scope of my invention.

I do not, therefore, restrict myself to the 125 details as shown in the drawings; but I intend to include also all mechanical equivalents and reasonably obvious modifications 130

of the same within the scope of my invention. I claim as my invention and desire to secure by Letters Patent:

1. In a stencil operating machine a table 5 for feeding thereon sheets of material, a stencil frame, a pair of movable supports therefor, situated at the opposite sides of said table and rigidly connected to each other, a means for raising and lowering said supports with said frame thereon, guide rods secured to each of said supports, to move therewith, and a means for keeping the motion of said rods vertical secured to said table, thereby keeping said frame in all 10 positions thereof parallel to said table.

2. In a stencil operating machine a table for feeding thereon sheets of material, a stencil frame, a pair of movable supports therefor, situated at the opposite sides of 20 said table and rigidly connected to each other, a means for raising and lowering said supports with said frame thereon into a position parallel to said table to bring said frame down on to said sheets, and registers secured to said supports to move therewith each in a straight line to limit the position of said sheets when fed on to said table.

3. In a stencil operating machine a table for feeding thereon sheets of material, a 30 stencil frame, a pair of movable supports therefor, situated at the opposite sides of said table and rigidly connected to each other, a means for raising and lowering said supports with said frame thereon into a position parallel to said table, to bring said frame down on to said sheets, registers adjustably secured to said supports to move therewith each in a straight line, to limit the position of said sheets when fed on to said table, and a means for adjusting the height 40 of said registers on said supports to correspond to various thicknesses of frames employed on the machine.

4. In a stencil operating machine a table 45 for feeding thereon sheets of material, a stencil frame, a pair of movable supports therefor, situated at the opposite sides of said table and rigidly connected to each other, a means for raising and lowering said supports with said frame thereon into a position parallel to said table, to bring said frame down on to said sheets, a means for detachably connecting the front of said frame to said supports and a means for 55 adjustably connecting the rear of said frame to said supports.

5. In a stencil operating machine a table for feeding thereon sheets of material, a stencil frame, a pair of movable supports 60 for said frame at the opposite sides of said table rigidly connected to each other, guide rods secured to each of said supports, a means for keeping the motion of said rods vertical, a lever, pivotally connected to one 65 of said supports, to actuate the same, and a

rocking link pivotally connected to said table and to said lever, to take up the irregularity of the motion of said lever.

6. In a stencil operating machine a table 70 for feeding thereon sheets of material, a stencil frame, a pair of movable supports therefor, situated at the opposite sides of said table, a rear beam and a front beam secured at their ends to and rigidly connecting to each other said supports, a cross beam mounted on the aforementioned beams, transversely thereto, a means for raising and lowering said supports with said beams and with said frame thereon into a position parallel to said table, to bring said frame 75 down on to said sheets, and registers adjustably secured to said rear beam and to said cross beam, to move therewith each in a straight line, to limit the position of said sheets when fed on to said table.

7. In a stencil operating machine a table for feeding thereon sheets of material, a stencil frame, a pair of movable supports therefor, situated at the opposite sides of said table, a rear beam and a front beam secured at their ends to and rigidly connecting to each other said supports, a cross-beam mounted on the aforementioned beams transversely thereto, a means for raising and lowering said supports with said beams and with said frame thereon into a position parallel to said table, to bring said frame down on to said sheets, feed screws carried by said rear beam and said cross beam, nuts engaged by said feed screws and registers adjustably secured by means of said nuts and screws to said rear beam and to said cross beam, to move therewith each in a straight line, to limit the position of said sheets when fed on to said table.

8. In a stencil operating machine a table for feeding thereon sheets of material, a stencil frame, a pair of movable supports therefor, situated at the opposite sides of said table and rigidly connected to each other, a means for raising and lowering said supports with said frame thereon into a position parallel to said table to bring said frame down on to said sheets, a front top bar detachably connected at the ends thereof to said supports, transversely thereto, a front longitudinal bar in said frame detachably connected to said front top bar, a rear longitudinal bar in said frame adjustably connected to said supports transversely thereto and cross-bars in said frame, secured at their ends to said longitudinal bars transversely thereto.

9. In a stencil operating machine a table for feeding thereon sheets of material, a stencil frame containing a front longitudinal bar and a rear longitudinal bar, a pair of movable supports for said frame, situated on opposite sides of said table and rigidly connected to each other, a clamp for de- 125 130

tachably connecting said rear longitudinal bar to said supports, a series of vertical openings at the upper edge of each of said supports, vertical screws to pass through said openings for detachably connecting said front longitudinal bar and said clamp to said supports, horizontal screws for ad-

justing the position of said rear longitudinal bar on said support before clamping it down thereon, and a means for raising and lowering said supports with said frame thereon into a position parallel to said table, to bring the frame down on to said sheets. 10

CHARLES ECKMAN.
